UNITED STATES PATENT OFFICE.

WILLIAM W. JONES, OF TOLEDO, OHIO.

DITCHER.

1,088,584.

Specification of Letters Patent.

Patented Feb. 24, 1914.

Application filed April 13, 1912. Serial No. 690,538.

To all whom it may concern:

Be it known that I, WILLIAM W. JONES, a citizen of the United States, residing at Toledo, in the county of Lucas and State of 5 Ohio, have invented new and useful Improvements in Ditchers, of which the following is a specification.

The general object of the invention is to so arrange and construct the several parts 10 of a ditcher as to obtain a ditcher of minimum weight and one requiring a minimum of power to operate it; and to this end the invention consists in certain improved constructions, arrangements and combinations 15 of devices, which will be more fully described hereinafter, and then pointed out in the claims.

Other objects will appear and be better understood from that embodiment of my invention of which the following is a specification, reference being had to the accompanying drawings forming part hereof, in which:

Figure 1 is a plan of the invention. Fig. 25 2 is a vertical longitudinal section on the line 2—2 of Fig. 1. Fig. 3 is a vertical cross section on the line 3—3 of Fig. 2. Fig. 4 is a detail of a portion of the excavating mechanism. Fig. 5 is a detail perspective 30 of the sections of the excavating tool or digger.

The machine forming the subject matter 35 of the present invention is intended chiefly for operating in soft soil, particularly swampy soil, such as is invariably found on reclaimed swamp. In operating with a ditcher on the last-named kind of land, it has, in most instances, been customary to employ the ditchers which are constructed 40 primarily for use in soft but high land.

This employment has resulted in many difficulties to those engaged in the work, and among the number existed that of preventing the machine from sinking in the land. 45

Since this tendency of the machine to sink was produced by its relatively great weight, the latter being due not only to the massiveness and relatively great number of parts used, but also to their disposition which was 50 such as to require for the operation, a relatively large and heavy motor, many contrivances were put forth having for their object to prevent the sinking of the machine by increasing the area of the bearing surface thereof. While the employment of 55 these devices rendered the machine more

buoyant, they, nevertheless, made it more cumbersome to handle, and the expense of installing them was, in many instances, a matter of no small moment. With their employment, however, certain facts still remained and among these were the complexity of the machine and the relatively great amount of power needed to operate the digging mechanism so as to lift the saturated soil. Experience in the handling of this soil shows that it offers comparatively no resistance to penetration for a distance equal to the depth of the ordinary ditch or drain. But a slice of about a foot in thickness and 60 three feet in length, offers material resistance to the implement employed to lift it and when such implement is a digger, it is at 65 once manifest that a greater amount of power is required to lift such a slice than a slice of corresponding size but of dry soil. Therefore, in carrying out one feature of 70 the present invention it is my aim to abandon the old idea of having the digger elevate the material and to call for no other 75 function from this element than that of penetrating the soil to the required depth and moving the sliced soil laterally, but to no appreciable distance upwardly.

In passing it may be stated that the ditch 80 formed with the old type of digger had vertical side walls which for obvious reasons, are useless in ditches made in swampy lands. Thus, the side walls of the ditch formed with the old type of digger had to 85 be slanted or beveled by hand by workmen following the ditcher. This proceeding while essential, was nevertheless, expensive 90 in that it involved the employment of a number of men. Therefore, in carrying out 95 another feature of my invention it has been my aim to eliminate the retreating of the sides of the ditch by manual labor and in this I have succeeded by substituting for the old one piece digger, one made up of a plurality of sections which enter the ground 100 from different points and which meet at the bottom of the ditch and interlock into a unitary structure after having cut a substantially wedge-shaped slice.

In the embodiment of the invention shown 105 in the drawings I suspend an apron of metal or other suitable material and of suitable contour such as rectangular, from a shaft 6 which is arranged in suitable bearings 110 7—7 at the upper ends of uprights 8—8 and in a bearing 9 carried by the upright por-

tion of a bracket 10 connected to one of the uprights 8.

The supporting frame 11, to the forward end portion of which the uprights 8—8 are suitably secured, may be formed of any desirable material such as angle iron and be of any suitable marginal contour and size. The frame is provided at its front end with a suitable pilot wheel 12 which is operated 10 to control the direction of progressive movement of the machine by a steering wheel 13 carried by a shaft 14 which has a bevel gear 15 meshing with a rack 16 on the yoke 17 in which the wheel 12 is fitted, and which is 15 journaled as indicated at 19, in the front end of the frame 11. The rear end portion of the machine is supported by suitable apron tractions 20—20 which are connected to telescoping shafts 21 and 22, the latter of which 20 is free to rotate on the inner. The shafts 21 and 22 are suitably connected such as by chain and sprocket connections 23—23 to sleeves 24—24 loose upon a shaft 25 which is suitably connected such as by chain and 25 sprocket connections 26, to a shaft 27 carried by the forward portion of the frame 11.

A suitable connection such as by means of bevel gears 28, is established between the shaft 27 and reversing gears 29—29 carried 30 by a sleeve 30 splined on a shaft 31 which is connected by suitable means such as chain and sprocket connections 32, with the crank shaft 33 of a motor 34 of a type suitable for the necessary movement. With the parts 35 positioned as shown in Fig. 1 and the motor turning in the required direction, the machine will progress to the right in the said figure and until the reversing lever 35 is shifted so as to cause the gear wheel 29 shown out of mesh in Fig. 1, to mesh with 40 one of the gear wheels 28, whereupon the machine will move in the opposite direction. To facilitate the turning of the machine either to the right or to the left, I unclutch 45 one of the clutches 36—36 splined on the shaft 25, from one of the sleeves 24. This is done by turning one of the hand wheels 37—37 at the forward end of the machine and within easy reach of the operator who 50 is positioned on the platform 38, it being understood that the steering wheels are so connected to the clutches as to reciprocate the same into and out of engagement with the clutch faces of the sleeves 24. Since 55 both clutches may be unclutched simultaneously by operating both hand wheels 37—37, it will be seen that the machine may be caused to stop when moving in either direction without requiring the stopping of the 60 motor and then again when only one clutch is unclutched motion will be imparted to only one of the apron tractions and when this has been accomplished and with the other apron traction stationary, the machine 65 may be readily turned.

As the machine progresses the apron 5 which is loose on the shaft 6, is oscillated by suitable mechanism such as an eccentric rod 39, connected to an eccentric 40 on the crank shaft 33. The digger *a* is so constructed and connected to the apron as to reciprocate thereon and to descend into contact with the ground when the apron swings to that end of its arc of movement nearest the front end of the machine. Now the connections for actuating the digger are such as to cause the same to descend into the ground for a predetermined distance and at a speed greater than the movement of the apron and such as to cause it, the said digger, to describe an arc in the ground as indicated in Fig. 2. Since the lower end of the cutting arc is at the bottom of the ditch, it will be manifest that as the apron moves toward that end of its arc of movement farthest from the front of the machine, the slice cut by the digger will be shoved rearwardly and onto the elevator *b*. Since the invention does not reside in the particular means for oscillating the apron and operating the digger, it will be understood that the descriptions of such means for operating the apron and that about to follow for operating the digger, are simply 90 illustrative.

The intermediate section 42 has a shank in the form of a rack 43 which is mounted to slide in a vertical guide 44 in the apron 5, while the side or end sections 45 and 46 have obliquely extending shanks in the form of racks 47—47 which are mounted to slide in oblique guides 48—48 on the apron 5. The inclination or the obliquity of the shanks 47—47 and guides 48—48 is such as to cause the sections 45 and 46 during the downward movement of the digger, to move for certain distances into the path of movement of the intermediate section 42. This movement of the sections 45 and 46 into the path of the intermediate section 42, is gradual and begins a trifle before the cutter completes its downward movement when the side portions *c* and *d* of the sections 45 and 46 begin to enter the mortises 50—50 made to receive them in the intermediate section and thus 100 continue to move into the mortises until the end of the downward movement of the cutter, at which time the sections 45 and 46 will be interlocked with the intermediate section, as shown in Fig. 4. The portions *e* and *f* of the sections 45—46 are arranged in angular relation to the portions *c* and *d* and while the latter are cutting in the same direction as the intermediate section 42 and also at an angle to the said section, the sections *e* and *f* are cutting so as to form the sleeping banks of the ditch and coöperating with the intermediate section 42 and portions *c* and *d* to block out a slice of earth. 105

The pinions 51 are loose on the shaft 6

and mesh with the racks 43 and 47—47 and the shaft 52 which is journaled in bearings 53—53 in the lower end portion of the apron, carries pinions 54—54 which are fast on the said shaft and also mesh with the racks 43 and 47—47. The clutch collars 55—55 are splined on the shaft 6 and are slid into and out of engagement with the pinions 51 by a suitable operating bar 57. 10 When the collars 55 are unclutched from the pinions 51, the digger may be operated manually by turning a hand wheel 58 on one end of the shaft 52. When the collars are clutched with the pinions 51 as shown in 15 Fig. 4, and the shaft 6 caused to rotate in one direction, the digger will be elevated or lowered depending on the direction in which the shaft 6 rotates. Inasmuch as it is essential to reciprocate the digger and have each 20 stroke thereof of a length somewhat greater than the depth of the ditch, I provide means adapted for rotating the shaft 6 for a predetermined number of revolutions in one direction and then automatically reversing 25 the movement of the shaft and causing it to rotate for the same number of revolutions or approximately so, in the opposite directions.

Referring now to Figs. 1 and 4 the opposed bevel gears 59—59 on the shaft 6, are arranged so as to mesh successively with the teeth of a mutilated bevel gear wheel 60 fast on a stub shaft 61 journaled in a bearing in the bracket 10 and in a bearing 62 on one of 35 the uprights 8. The bevel gear 63 fast on the lower end of the stub shaft 61, extends between the bevel gears 64—64 on a sleeve 65 splined on the shaft 31. The sleeve 65 is operated by suitable reversing mechanism 40 66 so as to cause either of the gears 64 to mesh with the gear 63. By providing the mechanism for reversing the shaft 61 the digger upon coming into contact with a log or other obstruction under the surface of the 45 soil, may be readily lifted or its action may be stopped by so moving the gears 64 as not to mesh with the gear 63.

The slice cut by the digger is deposited on the lower end of the endless apron 67 50 which is located between the sides 68—68 of the conveyer frame, which sides flare outwardly as shown in Fig. 1, to conform to the slant of the banks of the ditch. The lower end of the apron 67 passes over a roll 69 55 and its upper end over rolls 70 and 71. The position of the rolls 70 and 71 are such as to give a downward inclination to the upper end portion of the conveyer, whereby, the material may be conveniently discharged on 60 the laterals 72—72. The conveyer 67 has sprocket chains 73—73 which pass over sprocket wheels 74 on the lower roll 69 and sprocket wheels 75 and 76 on the upper rolls 70 and 71. Through the employment of 65 suitable means such as a sprocket 77 on the

shaft 24, a sprocket chain 78 and a sprocket wheel 79 on the shaft 80 journaled in bearings in the uprights 81—81 which support the conveying mechanism, motion is transmitted to the said shaft 80 and from thence by suitable mechanism such as a sprocket 82, a sprocket chain 83, a sprocket wheel 84 on a shaft 85 in bearings in the upper ends of the uprights 81, to the said shaft 85 which has fast upon it a spur gear 86 meshing 70 with a spur gear 87 on the roll 70. The rolls 88—88 at the upper ends of the laterals 72 are connected by meshing spur gears 89—89 fast on the rolls and the lower roll 90 of one of the laterals carries a bevel pinion 91 75 which meshes with a bevel pinion 92 on one end of the shaft 80.

The sides 68—68 of the conveyer, pivot on the shaft 70 and a cross bar 93 which passes through said side also passes through lugs having inclined slots one of which is shown in Fig. 2 and indicated by 94. A shoe 95 at the lower end of the conveyer is sharpened so as to enable it to readily pass through the soil and also has a curved surface in the arc of swing of the digger. This enables the digger to swing over the shoe and deposit the slice on the conveyer b.

What I claim as new is:

1. A digger for traction ditchers comprising a central section, end sections normally spaced from the central section and adapted to coöperate therewith to complete the digger, independent means for supporting the respective sections, and means for operating the supporting means, the supporting means of the end sections operating at an angle to the supporting means of the central section, the angle of operation of the end section supporting means with relation to the central section supporting means moving said end and central sections into digger forming co-operation prior to the limit of movement of all of the said supporting means toward digging position. 95

2. A digger for traction ditchers comprising a central section, end sections having cutters arranged at right angles to the central section, a frame, a supporting bar for each of said sections, and means carried by the frame for guiding the supporting bars of the end sections at an angle to the plane of movement of the supporting bar of the central section. 100

3. A digger for traction ditchers including a frame, a digger comprising a central section and end sections arranged to coöperate with the central section to complete the digger, a supporting bar carried by each of said central and end sections, and guiding means carried by the frame for each of said supporting bars, the guiding means for the supporting bars of the end sections converging downwardly toward the guiding means for the supporting bar of the central section. 115 120 125 130

4. A digger for traction ditchers including a frame, a digger comprising a central section and end sections arranged to coöperate with the central section to complete the digger, a supporting bar carried by each of said central and end sections, and guiding means carried by the frame for each of said supporting bars, the guiding means for the supporting bars of the end sections converging downwardly toward the guiding means for the supporting bar of the central section, the central and end sections being moved from a spaced relation to a digger forming coöperation during the operative movement of the digger as a whole.
5. A digger for traction ditchers including a frame, a digger comprising a central section and end sections arranged to coöperate with the central section to complete the digger, a supporting bar carried by each of said central and end sections, and guiding means carried by the frame for each of said supporting bars, the guiding means for the supporting bars of the end sections converging downwardly toward the guiding means for the supporting bar of the central section, and means for simultaneously and uniformly reciprocating said supporting bars in the guiding means.
6. A digger for traction ditchers including a frame, a digger comprising a central section and end sections arranged to coöperate with the central section to complete the digger, a supporting bar carried by each of said

central and end sections, and guiding means 35 carried by the frame for each of said supporting bars, the guiding means for the supporting bars of the end sections converging downwardly toward the guiding means for the supporting bar of the central section, 40 means for simultaneously and uniformly reciprocating said supporting bars in the guiding means, and means for imparting movement to the frame during the reciprocation of the supporting bars.

7. A digger for traction ditchers including a frame, a digger comprising a central section and end sections arranged to coöperate with the central section to complete the digger, a supporting bar carried by each of said 50 central and end sections, and guiding means carried by the frame for each of said supporting bars, the guiding means for the supporting bars of the end sections converging downwardly toward the guiding means for 55 the supporting bar of the central section, means for simultaneously and uniformly reciprocating said supporting bars in the guiding means, and means for imparting a swinging movement to the frame during the reciprocation of the supporting bars.

In testimony whereof I affix my signature in presence of two witnesses.

WILLIAM W. JONES.
